1 Claim. (Cl. 179—115.5)

This invention relates to devices utilizing a magnetic field and more particularly to a conductor coil in a transducer.

It is common practice to operate a conductor coil in an air gap having a strong magnetic field and to pass an electric current through the conductor coil causing it to move in the magnetic field, or to move the coil in the field to induce an electrical current in the coil. In some applications, the coil is moved from its neutral position by a momentary application of an electric current and is then returned to its neutral position by means of mechanical spring devices. Various types of solenoid switches, relays and transducers, such as microphones and loudspeakers operate in this manner.

More specifically and by way of example, in a moving coil or electrodynamic loudspeaker, a voice coil is affixed to the apex of a cone or diaphragm which is flexibly supported on a frame at the base diameter of the cone by an annular cloth ring called a "surround," and is also supported at the voice coil connection by a smaller, flexible annular ring called a "spider." The voice coil is generally mounted with its axis at right angles to magnetic lines of flux in a strong magnetic field, that is produced by a ring magnet and pole piece attached to the under side of the speaker frame. The "surround" and the "spider" centrally locate the voice coil and cone and hold them in a neutral axial position about the pole piece. An audio frequency output from an amplifier is passed through the voice coil and causes a force to be exerted in a direction of the axis of the coil, displacing the coil in the magnetic field, the displacement varying with the magnitude of the current passing through the coil.

The flexible nature of the supporting devices allows the coil movement and also supplies a spring or mechanical restoring force to move the coil back to its neutral position when the amplifier frequency is at zero. The coil and diaphragm move back and forth in an axial direction due to a variation in the amplitude of the audio signal and produce audible sound. The coil restoring force should increase linearly with the displacement force in order to accurately reproduce the audio output of the amplifier, but an actual loudspeaker system, such restoring force is non-linear and such non-linearity increases rapidly as the displacement force is increased, causing serious distortion of the sound waves and undesirable resonances, especially when transient impulses of a high amplitude are impressed upon the voice coil. The same defect is found in a dynamic microphone.

A primary object of this invention is to provide a new and novel voice coil for an electrodynamic loudspeaker or other transducers that will allow them to respond to sound waves and transient impulses and transmit said waves and impulses free from undesirable resonances and distortion.

Another object of this invention is to provide a non-mechanical restoring force for a moving conductor in an electro-magnetic system.

Another object of this invention is to provide a magnetic

2

restoring force for a moving voice coil in an electrodynamic loudspeaker or other transducer that is generally linear with respect to the coil displacing force, completely reactive to transient impulses and free from undesirable resonances, thereby relegating the function of mechanical suspension devices, as far as possible, to that of centering the coil during movement.

Another object of this invention is to provide a voice coil for a transducer comprising a magnetic material that is spatially coexistent with the current carrying conductor.

Still another object of this invention is to provide a low reluctance path to magnetic lines of flux in an electro-magnetic system which results in the linear return of a conductor that has been displaced in a magnetic field to its original or neutral position, and which may be used in transient switching devices, remote positioning devices, transducers and any electro-magnetic device dependent upon a spring action for zero positioning.

Further objects and advantages will become apparent from the following detailed description taken in connection with the accompanying drawings, in which:

FIGURE 1 is a cross-sectional elevation of an electrodynamic loudspeaker embodying the invention.

FIGURE 2 is an enlarged view of the voice coil cross section shown in FIGURE 1.

FIGURES 3 and 4 are traces as shown by an oscilloscope comparing the operation of applicant's loudspeakers with that of a conventional speaker.

While this invention is susceptible to embodiments of different forms, there is shown in the drawings and will herein be described in detail an embodiment of the invention with the understanding that the present disclosure is to be considered as an exemplification of the principles of the invention, and is not intended to limit the invention to the embodiment illustrated. The scope of the invention will be pointed out in the appended claims.

Referring to the drawing, a suitable supporting structure for a loudspeaker is shown, including a permanent ring magnet 4 with a plate 5, having a centrally located hole 6 therein, mounted on its top surface, and a circular plate 7 with a centrally disposed cylindrical pole piece 8, mounted on the bottom surface of magnet 4. The plates are secured to ring magnet 4 by a plurality of tie bolts 9. The pole piece 8 is smaller in diameter at its top portion than the hole 6 and extends axially upward through the ring magnet 4 and the hole 6 terminating near the top surface of the plate 5. A strong magnetic field is established by the magnet 4 in a circular air gap formed between the surface of hole 6 and the outer surface of pole piece 8. A plurality of upwardly and outwardly extending legs 10 originate at the outer periphery of plate 5 and terminate in an annular ring 11 to form the "basket" of the loudspeaker and a felt ring 11a is cemented to the top surface of ring 11 providing a cushion for mounting the loudspeaker.

The operating or moving components of applicant's loudspeaker consist of a cone-shaped diaphragm 12, which may be of the conventional type, affixed at its apex to the end portion of a hollow cylindrical voice coil 13. The diaphragm 12 and the coil 13 are mounted in the loudspeaker supporting structure in such a manner that the voice coil is concentric with and surrounds the pole piece 8 and is free to move axially in the air gap.

The means for supporting the diaphragm and coil

consist of an annular ring or "surround" 15 of cloth or other flexible material forming a flexible connection between the "basket" rim 11 and the base portion of the diaphragm 12. Additional support for the diaphragm and coil is provided by an annular ring or "spider" 16 of flexible sheet material affixed to the voice coil adjacent its connection to the apex of the diaphragm and to the top plate 5, forming a flexible connection therebetween.

The "spider" 16 which supports the voice coil 13 in the speaker frame is made more flexible in applicant's loudspeaker than in a conventional loudspeaker for the purpose of utilizing the suspension device as centering means only, to keep the coil in axial alignment as it is moved in the air gap, and to afford very little, if any, opposition or restoring force to the movement of the coil.

A preferred form of applicant's voice coil is shown in FIGURE 2 and comprises a cylindrical aluminum tube 20 having its outer surface precoated with a silicone rubber 21. A cylindrical paper form 22 having a band of magnetic material 23 disposed on its outer surface extending from the edge to the center of the form is cemented concentrically about the tube 20, and a conductor 24 is wound in a double layer coil over the 25 magnetic material. The ends of the conductor 24 are extended out to one of the legs 10 and terminate in a connection 25.

In operation, the magnetic material 23 of the coil 13 offers a relatively low reluctance path for the magnetic lines of flux in the air gap and as the coil is displaced axially upward or downward from its neutral position in the air gap, by an audio signal applied to the voice coil, the magnetic flux will follow the path of low reluctance offered by the magnetic material rather than the path of high reluctance offered by the air gap. As the magnetic lines of flux follow the magnetic material, they are bent in the direction of coil movement and act to restore the coil to its neutral position when the displacement force is removed or reduced to zero. 40 The flux lines act as a "magnetic spring" producing a coil restoring force that is completely linear to the coil displacing force.

Various methods of coil construction may be resorted to in order to produce a magnetic material spacially co-existent with a conductor coil, and a few are enumerated in the following examples:

Example I

An iron powder is sprinkled onto the sticky surface of ordinary masking tape and an adhesive applied to the inside surface of a conventional voice coil comprising a conductor wound on a cylindrical paper form. The sticky side of the masking tape is then pressed against the adhesive and allowed to dry after which a solvent is applied to the masking tape removing it and leaving the iron powder attached to the inside surface of the coil form.

Example II

A self-supporting double layer cylindrical coiled conductor is cemented to the outside surface of a cylindrical aluminum tube and the outside surface of the coil coated with a catalyzed epoxy resin, dusted with iron powder and allowed to cure.

Example III

An adhesive cement is made up with a low viscosity epoxy resin and iron powder, and used for fastening the turns of a two-layer cylindrical conductor coil together as well as to cement the coil to the outer surface of a cylindrical paper form.

Example IV

A strip of paper coated on one side with a band of catalyzed resin has iron powder dusted onto and rolled into the band, as with a rubber roller, and allowed to cure. The paper is cemented to the outer surface of a cylindrical aluminum tube onto which a thin layer of silicone rubber has been precoated. A double layer of conductor coil is wound about the magnetic band. The rubber coating acts as a yieldable surface between the tube and the conductor winding.

Example V

A coil as in Example IV except that a double band of magnetic material is used, one on each side of the paper strip.

Example VI

A magnetic iron conductor is wound about the outer surface of a cylindrical paper form.

Example VII

A layer of magnetic iron foil is formed about and affixed to the outer surface of a cylindrical paper form and a conductor wound about the iron foil.

The above examples show that the voice coil of applicant's invention can be made up in many various ways. It should be noted that the greater the amount of magnetic material used in the construction of the coil, the lower the reluctance to the magnetic line of flux.

The curves of FIGURES 3 and 4 show a comparison between the restoring forces operating on a loudspeaker coil having a magnetic material disposed coaxially with the coil conductor as described in Example V and an identical speaker coil but without the magnetic material, as measured on an oscilloscope. In each instance, the coils were placed on a magnetic structure and fastened with a "spider" except that the "spider" used with the magnetic coil was of a larger diameter in order to form a more flexible mounting and relegate its function to centering purposes only. The coils were raised a fixed distance above the gap and released. It can be said that if there were no inductance in the coil, and no initial forces or gravitational forces that the trace would be a straight line. The trace shown in FIGURE 3 is the result obtained from the magnetic coil and it can be seen that the restoring force is completely linear. In FIGURE 4, the trace obtained by the non-magnetic coil shows a slow take-off which is due to the restriction offered by the "spider" and a non-linear restoring force where considerable bouncing took place due to the "spider." It is apparent from viewing the two curves that the restoring force offered by the "magnetic spring" effect is superior to the mechanical "spider" device since the restoring force of the "magnetic spring" is completely linear to the coil displacing force.

Utilizing applicant's invention in a loudspeaker results in excellent time constants when transient impulses are imposed on the voice coil. Because of the linear restoring force provided by the "magnetic spring" effect, applications for applicant's invention include, any device dependent upon spring action for zero positioning, such as meters, relays, transient switching devices and remote positioning devices.

I claim:

A transducer comprising: a voice coil consisting of a cylindrical non-magnetic form with a current conductor wound about its outer surface and having a magnetic material and a thin layer of yieldable material interposed between said conductor and said outer surface; a cylindrical pole piece having lines of magnetic flux extending radially outward therefrom; means for mounting said voice coil concentric with and about said pole piece so that said coil is free to move in its axial direction from a

neutral position; means for moving said voice coil in a direction at right angles to said lines of magnetic flux; and means for bending said flux lines in the direction of coil movement including a low reluctance path to said flux lines offered by said magnetic material and which serves as the principal force to return the coil to its neutral position.
